[57] **CLAIM**

The ornamental design for a combined refillable eraser tips and container therefor, as shown and described.

DESCRIPTION

FIG. 1 is a front elevational view of a combined refillable eraser tips and container therefor showing my new design;

FIG. 2 is a right side elevational view thereof, the left side being a mirror image thereof;

FIG. 3 is a top plan view thereof;

FIG. 4 is a bottom plan view thereof;

FIG. 5 is a rear elevational view thereof; and,

FIG. 6 is a cross-sectional view thereof taken along the line of 6—6 of FIG. 1.

FIG. 1

FIG. 2

FIG. 3

FIG. 4

FIG.5
